(57) **CLAIM**

I claim the ornamental design for the “ammunition and casing removal tool,” as shown and described.

DESCRIPTION

FIG. 1 is a top perspective view of the “ammunition and casing removal tool,” showing my new design;

FIG. 2 is a top plan view thereof;

FIG. 3 is a bottom plan view thereof;

FIG. 4 is a right-side elevation view thereof, the left-side view being a mirror image of that shown;

FIG. 5 is a front elevation view thereof; and,

FIG. 6 is a rear elevation view thereof.
